(57) **CLAIM**

The ornamental design for the combination of a tray and an arrangement of shrimp, as shown and described.

DESCRIPTION

FIG. 1 is a perspective view of a combination of a tray and an arrangement of shrimp showing my new design;

FIG. 2 is a top plan view thereof;

FIG. 3 is a side view thereof;

FIG. 4 is a perspective view of a tray; without shrimp and central piece; shown separately for clarity;

FIG. 5 is a top plan view of FIG. 4; and,

FIG. 6 is a side view of FIG. 4.
